US00D686188S

(12) **United States Design Patent**
Jeong et al.

(10) **Patent No.:** US D686,188 S
(45) **Date of Patent:** ** Jul. 16, 2013

(54) **WIRELESS IMAGE RECEIVER**

(75) Inventors: **Kwang-Seok Jeong**, Changwon (KR);
Se-Mi Jang, Changwon (KR); **Joo-Bok Kim**, Changwon (KM)

(73) Assignee: **Samsung Techwin Co., Ltd.**, Changwon (KR)

(**) Term: **14 Years**

(21) Appl. No.: **29/412,121**

(22) Filed: **Jan. 31, 2012**
